UNITED STATES PATENT OFFICE.

JOHN A. HALL, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

1,360,738.

Specification of Letters Patent.

Patented Nov. 30, 1920.

Application filed July 24, 1917. Serial No. 182,465.

To all whom it may concern:

Be it known that I, JOHN A. HALL, a citizen of the United States, residing at East Orange, in the county of Essex and State of New Jersey, have invented certain new and useful Improvements in Telephone Systems, of which the following is a full, clear, concise, and exact description.

This invention relates to telephone systems of the type employing machine switching, and is related more particularly to means for establishing connections between subscribers' substations in systems of great capacity.

15 The invention has for its object the provision of means for overcoming the psychological difficulty usually experienced in establishing connections in automatic telephone systems of great capacity. Usually 20 the decimal system of designating telephones is used, whence in systems exceeding one hundred thousand subscribers' substations, the proper manipulation of the dial switch in calling becomes psychologically 25 difficult, not to say impossible, when the fact that only a very few failures to get the right party in the total number called makes the difference between a commercial success and a commercial failure, is considered. The object, then, is to provide means 30 for operating a system of unlimited capacity free from the objection thus attached to the ordinary system as it would be if its capacity were greatly increased.

35 Attempts have heretofore been made to increase the capacity of an automatic system and still avoid the difficulty mentioned. The means employed were in almost every case far from the standard practice of the 40 present day, and so far few have proved commercial. As an instance, it has been proposed to increase the number of ways that each digital position of a telephone 45 designation can be filled, by using letters or other distinctive characters in addition to the usual ten digits. This scheme, however, contemplates the use of apparatus of largely increased capacity and quite different from that being manufactured at the present time. 50 Another object of the invention, then, is to so arrange the present system that standard apparatus, dial switches, selectors, connectors and so forth, built for use in decimal systems, can be utilized.

55 According to a feature of this invention

selective operations are carried out not only in accordance with the characters of the digits composing a telephone designation, but also in accordance with the number of digits. Thus a connection will be extended 60 over one path if the called telephone designation contains four digits and over another path if the called telephone designation contains seven digits.

According to another feature of this invention, all telephone designations contain the same number of digits though the greater percentage are called through the use of abbreviated designations of varying and much smaller numbers of digits than 65 the actual designations. The entire system may be thus divided into a definite number of districts—geographical or otherwise, and calls established from substation to substation within a district through the use of the 70 abbreviated designation. Calls from a substation within one district to a substation within another district, however, are established through the use of the full designation.

Though but one abbreviation of a designation has been provided for in the preferred arrangement shown in the drawings, yet it is believed to be fully within the scope and the spirit of the invention to use a second or greater number of abbreviations, 85 whereby the districts may be subdivided and the subdivisions further divided in any manner that the conditions of traffic make advisable.

According to another feature of the invention the total number of permutations of digits in a given number of digital positions may be used for designations. In systems heretofore devised either an extra position 90 was provided on the dial switches and first selectors or all numbers beginning with a certain digit (constituting ten per cent. in the decimal system) were reserved for special service such as "long distance" calls. 95

The present invention makes this addition to the apparatus or subtraction from the total number of available designations unnecessary since the very nature of the long distance call—that is, the use of the 100 full designation rather than the abbreviated designation—causes a different switching operation to take place.

In the drawings, consisting of three figures, so much of a telephone system as is 105

necessary to disclose the features of this invention is shown. Figure 1 diagrammatically represents a calling substation, a line finder switch, an allotter switch and circuits extending to selector switches, whereby a connection may be established. Fig. 2 (placed beneath Fig. 1) diagrammatically represents a number of registers for receiving impulses from a calling substation, the registers being associated with the line finder switch through the allotter switch. Fig. 3 (placed to the right of Fig. 2) diagrammatically represents an impulse transmitter which is automatically actuated when a call has been registered.

General arrangement of system.

In the general arrangement of this system each substation has a separate and distinct numerical designation. The system then is divided into districts, and as illustrated, all designations in each district have the same first three digits.

All digits are then reversed and are listed so that it appears that all designations in each district are the same as regards the last three.

In the actual listing only the then first four digits are given as the designation—the then remaining three being given under the head of special instructions to subscribers in other districts who wish to make a foreign district or long distance call to a station in the district being considered.

In making a call the impulses sent according to the listing and, therefore, in reverse order to the actual designation of the called line, are received by a set of registers. If the call be one to a substation in the same district, then only four registers will be set and a slow acting mechanism will act to set in operation an impulse transmitter. If, on the other hand the call be one to a substation in another district then an additional three registers will be set in accordance with the common three digits of all substations in that district, the slow acting mechanism will fail to operate and as a consequence, the means for starting the impulse transmitter will in this case cause a switching operation to take place and extend the call over a different path.

The impulses, as has been said, are received and recorded by a set of registers and as soon as all are received, which is determined by the slow acting mechanism in the case of an abbreviated designation and by the full use of the apparatus in the case of the full designation, then an impulse transmitter is set in operation. In its operation, this transmitter reverses the order of the digits, so that the setting of the selector switches is in accordance with the actual numerical designations of the substations.

Thereafter the further progress of the call

is the same as in any other well known step-by-step system.

Detailed description of operation.

Referring now to the drawings it will be shown how a subscriber at substation 100 may, by manipulation of his dial switch 101, establish a connection to a substation within the same district over the local trunk 102, or to a substation within a foreign district 75 over the local district trunk 103.

It will be assumed that the designation of the called substation within the foreign district is 1,726,385, and that the designation of the substation within the same district is 80 1536385. From this it will appear that the district in which this call originates is characterized in that the designation of each substation begins with the digits 153, and that the foreign district is characterized in 85 that the designations of the substations begin with the digits 172.

According to the directories used by the subscribers in these districts it will appear, however, that each of the called substations 90 has a designation 5836, that is, the reverse of the last four digits in each designation.

To the party originating a call in the local district the directions for calling instruct him to manipulate his dial switch in accordance with the abbreviated designation 5836, no mention being made of the digits 351 (the reverse of 153) which characterize the local district. The directions to the same subscriber for calling 271 in the foreign district instruct him to add the digits or in other words to manipulate his dial switch to send a train of impulses representing the digits 5836271.

Accordingly, the great percentage of the 105 traffic which terminates in the same district in which it originates is carried on through the use of the abbreviated designations whereby it appears to the ordinary telephone user that the system is of ordinary dimensions. Only to the class of subscribers 110 who originate long distance calls, then, does the duty of manipulating their dial switches in accordance with the full designations devolve. In other words, the more 115 intelligent class of people who make long distance calls or those psychologically fitted to properly remember and transmit long series of digits are the only ones required to do so.

It will therefore be first shown how a subscriber at substation 100 establishes a local connection through the use of the abbreviated designation 5836 and second, how the subscriber at substation 100 may establish a 125 long distance connection through the use of the full designation 5836271.

Removal of the receiver from its switchhook at the substation 100 establishes a circuit for the energization of the line relay 130

104, extending from ground, the left-hand winding of relay 104, outer left-hand armature, and contact of cut-off relay 105, to and through the apparatus of the substation 100 5 including the dial switch 101, the contact and inner left-hand armature of relay 105, right-hand winding of relay 104, to battery and ground. Relay 104 attracts its armature and establishes a circuit for the energization of group relay 106, from ground, inner armature and contact 104, winding of relay 106, to battery and ground. In turn, relay 106 attracts its armatures and energizes starter relay 107 through a circuit 10 extending from the ground, and right-hand armature of relay 106, winding of relay 107, to battery and ground. When relay 107 is energized the starter wire 108 is grounded at its contact and armature, and a circuit for 15 the energization of the primary magnet 110 is established in an allotted line finder switch.

It should be noted at this point that the 20 starter wire 108 extends to a plurality of line finder switches, one or more of which may be allotted and ready for service. It should also be noted that a circuit extends from ground, contact and armature of starter relay 107, side-switch wiper 109 25 and its first position contact, contact and armature of primary magnet 110, winding of primary magnet 110, winding of relay 111, to battery and ground. The current flowing over this circuit, however, is too 30 small to cause the energization of the primary magnet in a switch which is not as yet allotted. In a switch which is allotted, however, the relay 111 is shunted through a parallel path extending from the winding 35 of relay 110, contact 112, wiper 113, conductor 114, sequence switch contact 300 (first position), sequence switch contact 301 (first position) to battery and ground.

The primary magnet 110, through the 40 attraction of its armatures in this last described circuit, breaks its own circuit and in the well-known manner steps the shaft carrying brushes 115, 116, 117 and 118 around until the latter makes contact with 45 the terminal 119. A circuit is thereupon established from ground, contact and right-hand armature of relay 106, terminal 119, brush 118, first position contact and side-switch wiper 120, winding of escape magnet 50 121, winding of primary magnet 110, and thence to battery over the circuit previously described. Through the current flowing in this circuit the escape magnet 121 is energized, the primary magnet 110 is held in the 55 energized position, and the further rotation of the brush shaft is prevented.

The energization of the escape magnet 121 causes the movement of the side-switch wipers into their second positions, where- 60 65 upon a circuit is established from ground,

the armature and contact of relay 122, second position contact and side-switch wiper 120, thence over the circuit previously described through the windings of relay 121 and magnet 110.

Through the movement of the side-switch wiper 109, a circuit is established for the energization of the secondary magnet 123, extending from ground, contact and armature of relay 107, starter wire 108, side-switch 70 wiper 109 and its second position contact, contact and armature of secondary magnet 123, winding of magnet 123, to battery and ground.

Through the automatic action of the secondary magnet, brushes 115 to 117 are moved over their associated terminals until the terminals 124 to 126 are encountered. During this movement a circuit is established from grounded battery, the winding 80 of cut-off relay 105 of other line terminals similar to 124, brush 115, side-switch wiper 128 and its second position contact, winding of marginal relay 122 to ground. The current flowing over this circuit is insufficient 90 to cause an energization of either relay 105 or relay 122. However, the terminal 124 connected with the calling substation will have a potential of a different magnitude impressed upon it through the resistance coil 95 127 the contact and left-hand armature of relay 106, contact and outer right-hand armature of relay 104 to terminal 124, through which relay 122 will be sufficiently energized to cause it to attract its armature. 100 Therefore, when the brush 115 encounters terminal 124 of the calling line, the relay 122 will be energized, and the circuit for the energization of escape magnet 121 will be opened.

The deenergization of relay 121 results in the movement of the side-switch wipers into their third positions, whereupon relay 105 will be energized over a circuit extending from ground, the third position contact and side-switch wiper 128, the brush 115, the terminal 124, winding of relay 105, to battery and ground. The energization of relay 105 in the well-known manner will cause the deenergization of line relay 104, the group 115 relay 106 and the starter relay 107.

The movement of the side-switch wipers into their third positions puts the substation 100 into control of the registers diagrammatically shown in Fig. 2, and a circuit is 120 established from ground, battery, the right-hand winding of relay 200, the normal contact and inner left-hand armature of relay 201, conductor 202, brush 129, contact 130, third position contact and side-switch wiper 125 131, brush 117, terminal 126 to and through the apparatus at substation 100 including dial switch 101, terminal 125, brush 116, side-switch wiper 132 and its third-position contact, contact 133, brush 134, conductor 130

203, outer left-hand armature and normal contact of relay 201, left-hand winding of relay 200 to ground.

Relay 200 is energized in this circuit and 5 attracts its armature, whereby a circuit is established for the energization of the motor magnet 204. It should be noted at this point that the motor magnet 204 is the actuating means for a step-by-step sequence 10 switch similar in construction to that shown in United States Patent No. 1127808 of February 9, 1915 to Reynolds and Baldwin. The operation of the present structure is somewhat different in that it is not under 15 control of a constantly rotating roller as in the patent cited but is controlled through a well known pawl and ratchet means.

The energization of magnet 204 causes the 20 movements of the associated sequence switch contacts into position 2, whereupon the apparatus is in condition to receive impulses from the subscriber's line.

According to the designation of the called 25 telephone the subscriber will first manipulate his dial switch 101 in accordance with the digit 5, thereby causing five rapid interruptions of the line circuit. Upon the first such interruption, the relay 200 is deenergized and in retracting its armatures establishes a circuit for the energization of the 30 slow release relay 206, such circuit extending from ground, sequence switch 205 (positions 2 to 12), the contact and right-hand armature of relay 200, the winding of relay 35 206, to battery and ground. In this circuit, this relay remains energized until after the last momentary deenergization of the relay 200, when, due to the long energization thereof, its circuit will be permanently 40 opened and it will retract its armatures, thereupon establishing a circuit for the energization of relay 201 extending from ground, sequence switch contact 205 (positions 3 to 45 12), contact and armature of relay 206, winding of relay 201, to battery and ground. Relay 201, in attracting its armatures, establishes a holding circuit for itself extending from ground, sequence switch contact 205 (positions 3 to 12), right-hand armature 50 and contact of relay 201, the winding of relay 201, to battery and ground.

Upon each energization after a momentary deenergization of relay 200, a circuit for the energization of motor magnet 204 is 55 established, as before described, and the sequence switch contacts are advanced step by step through the sending of five impulses as in the present case. The sequence switch is stepped into its seventh position, thereby 60 closing the sequence switch contact 207 (position 7), the function of which will be hereinafter described.

At the end of the first series of five impulses relay 201 is energized as described, 65 and the conductors 202 and 203 which are

up to this time extended to the windings of relay 200 are now switched to the windings of a similar relay 210, not shown, in a second register where the second digit of the called 70 substation is registered.

In a similar manner the third digit of the designation is registered on a third register and after the operation of the slow release relay therein the lines leading to the substation are switched to the windings of relay 210. 75 The subsequent action of the fourth register under control of relay 210 is in every respect similar to that described in connection with the first register except that due to the receipt of six impulses it will be set in 80 position 8, and sequence switch contact 212 (position 8), will be closed for a purpose to be hereafter described.

Thereafter, the conductors 202 and 203 are switched from association with relay 210 85 into association with relay 220 through the contacts of relay 221. In a manner similar to that described, relay 220 attracts its armatures, causes the energization of motor magnet 224 and thereby causes the movement of the associated sequence switch contact into position 2.

A circuit is now established from ground, sequence switch contact 222 (position 2), winding of relay 221 to battery and ground. 95 Relay 221 is a slow-acting mechanism, being illustrated in this case as a dash pot type of relay. The energization of such a relay results in the attraction of its armatures only after a definite period of time has 100 elapsed, which period of time may be adjusted to meet any requirement.

In the present case, this relay is so adjusted that it will not energize until a sufficient time has elapsed to indicate that no 105 more impulses will be transmitted over the circuit leading from the substation. When said period of time has elapsed therefore, the relay attracts its armatures and transfers the circuit leading from the substation from control relay 220 to control relay 302. The circuit for the energization of relay 302 may be traced from ground, battery, winding of relay 302, sequence switch contact 303 (position 1), conductor 304, alternate contact and inner armature of relay 221, alternate contact and outer left-hand armature of relay 211, alternate contact and outer left-hand armature of relay 201, conductor 203, thence over the circuit previously traced to conductor 202, inner left-hand armature and alternate contact of relay 201, inner left-hand armature and alternate contact of relay 211 outer right-hand armature and alternate contact of relay 221, conductor 305, 120 sequence switch contact 306 (position 1), left-hand winding of relay 302 to ground. 125

Relay 302 is energized in this circuit and thereupon establishes a circuit for the energization of motor magnet 307, extending 130

from ground, contact and armature of relay 302, winding of motor magnet 307 to battery and ground. Motor magnet 307 controls a sequence switch similar to those used 5 as registers heretofore described and upon its present energization drives its associated contacts into their second positions. Thereupon, the impulse transmitter is caused to operate.

10 In position 2 of the sequence switch, under control of the motor magnet 307 a circuit is established for the energization of relay 111 and the consequent seizure of the local trunk 102. This circuit extends from 15 ground, sequence switch contact 308 (position 2), conductor 114, wiper 113, contact 112, winding of relay 111 to battery and ground. Relay 111 thereupon attracts its armatures and establishes a locking circuit 20 for itself from its winding, its contact and inner lower armature over the side-switch wiper 128 and its third position contact to ground.

Thereupon, the selector switch which may 25 be of any well-known type, connected to the local trunk 102 is seized through a path of low resistance being bridged from terminal 135 to 136 as follows: from terminal 135, alternate contact and upper armature of 30 relay 111, contact 139, brush 140, conductor 141, sequence switch contact 309 (positions 2 to 11), sequence switch contact 309 (position 2), sequence switch contact 310 (position 2), sequence switch contact 310 (positions 2 to 11), conductor 142, brush 143, contact 144, inner upper armature and alternate contact of relay 111, to terminal 136.

40 In position 2 of the sequence switch controlled by motor magnet 307, a circuit is established from ground, interrupter 311, sequence switch contact 312, (position 2), the winding of motor magnet 307 to battery and ground. Motor magnet 307 is energized and by moving its contact into the third position, opens the circuit just traced. Thereupon, a circuit will be established from ground, sequence switch contact 313 (position 3), contact and right-hand armature 45 of relay 314 to battery and ground.

50 It should be noted at this point that the conductors 141 and 142 which extend to the selector switch on the local trunk 102 are connected through sequence switch contacts 309 and 310 respectively, to the contact and left-hand armature of relay 314 through which a bridge of low resistance is put on such selector switch until the relay 314 is energized.

55 The circuit just described for the energization of relay 314 causes it to attract its armatures and at the same time move the wiper 315 step by step over its associated contacts. Each time that it moves its armature, the bridge of low resistance upon the local trunk is momentarily opened in a

manner similar to the action caused by the subscriber's dial switch, whereby the selector is actuated.

It will be noted that sequence switch contact 316 is closed in the third position and extends a ground over the conductor 317 to the sequence switch contact 212 in its eighth position and thence over the conductor 213 to the contact 318. As the brush 315 encounters the contact 318 after taking six steps, 70 and after the circuit extending through conductors 141 and 142 has been opened six times and the selector switch on the local trunk has therefore been driven to its sixth selective position, a circuit will be established from the ground on contact 318 to brush 315, the commutator segment 319 in association with the brush 315, the winding of relay 320 to battery and ground. Relay 320 short-circuits the contact and left-hand 75 armature of relay 314 through its contact and left-hand armature and at the same time establishes a holding circuit for itself which is maintained until the brush 315 has again reached normal position. Such circuit may 80 be traced from ground, the contact and right-hand armature 320, the brush 315, commutator segment 319, the winding of relay 320 to battery and ground. 85

90 As the brush 315 encounters the grounded contact 318, a circuit is established from such ground, the brush 315, the commutator segment 319, sequence switch contact 312 (positions 3 to 10), the winding of motor magnet 307 to battery and ground. The motor magnet 95 is energized in this circuit and the sequence switch contacts are moved to their fourth positions, but the motor magnet is not deenergized until the brush 315 is disconnected from the commutator segment 319 100 at its normal position. The circuit for the energization of relay 314 is maintained over a circuit from ground, contact and right-hand armature of relay 320, sequence switch contact 313 (position 4) and thence over the 105 circuit previously traced.

When the brush 315 reaches its normal position relay 320 is deenergized and in turn relay 314 is deenergized so that the brush is halted until the sequence switch is moved 110 into a new position.

Upon the deenergization of relay 320, motor magnet 307 is momentarily deenergized, whereupon a new energizing circuit is established from ground, interrupter 311, sequence switch contact 312 (position 4), 115 winding of motor magnet 307 to battery and ground and the sequence switch contacts are driven into their fifth positions.

120 In the fifth position a ground is extended to the register contacts of the third register through sequence switch contact 316 (position 5), and conductor 321, whereby the contact 322 is grounded, the brush 315 takes three steps, the circuit leading to the local 125 130

trunk 102 is opened three times, and the second selector switch thereon is driven to its third selecting position in a manner similar to that described in connection with the 5 fourth register.

Thereafter, the sequence switch under control of the motor magnet 307 passes through its positions successively and the impulse transmitter causes the actuation of the 10 selector and connector switches over the local trunk 102 until the connector switch is driven into association with the terminals of the desired line, at which time the sequence switch under control of motor magnet 307 15 is left in the eleventh position and a circuit is established from ground, battery, sequence switch contact 301 (position 11), conductor 323, contact and left-hand armature of relay 145, wiper 146, contact 147, third 20 position contact and side switch wiper 120, winding of escape magnet 121, winding of primary magnet 110, contact and inner lower armature of relay 111, side-switch wiper 128 and its third position contact to ground. The 25 energization of the escape magnet 121 causes the movement of the side-switch wipers into their fourth positions, whereupon, the circuit from the substation 100 is directly connected to the local trunk 102 through the 30 side-switch wipers 131 and 132 in their fourth positions.

In the fourth position a circuit is established from ground, the fourth position contact and side-switch wiper 148, contact 147, 35 wiper 146, winding of relay 145 to battery and ground.

It should be noted at this point that relay 145 is of such resistance that it will neither be energized or cause sufficient current to 40 flow to energize the relays 121 or 110 through which the circuit is formed in the third positions of the side-switch wipers. When a direct ground, however, is placed on its winding as in the present case, it is 45 energized, and upon attracting its armatures it establishes a circuit from ground, the contact and right-hand armature of relay 145, the contact and armature of magnet 149, the winding thereof to battery and 50 ground. Magnet 149 causes the brushes 146, 113, 129, 140, 134 and 143 to be stepped around over their associated contacts until the contact 147, free of ground and which therefore denotes an idle line finder switch. 55 is encountered, whereupon, the relay 145 de-energizes and by opening the circuit of relay 149 causes the brushes to rest in association with contacts leading to such idle line finder switch.

60 In position 11 of the sequence switch under control of motor magnet 307 a circuit is established from ground, interrupter 311, sequence switch contact 312 (position 11), winding of motor magnet 307 to battery and ground. Motor magnet 307 is energized in

this circuit, whereupon the associated sequence switch contacts are driven into position 12.

In position 12, a circuit is established from ground, interrupter 324, sequence 70 switch contact 325 (position 12), conductor 326, and thence through sequence switch contacts 215 and 208 and through similar sequence switch contacts to the windings of the associated motor magnets. Such sequence switch contacts being in each case closed in their positions 3 to 18 inclusive. Under the influence of the interrupter 324 each one of the sequence switches used as 75 registers will be returned step by step to 80 their first positions, and when the last one reaches its first position a circuit is established from ground, sequence switch contact 209 (position 1), sequence switch contact 216, (position 1), sequence switch contact 225, (position 1), sequence switch contact 235 (position 1), conductor 327, sequence switch contact 312 (position 12), winding of motor magnet 307 to battery and ground. Motor magnet 307 is energized in this circuit and moves its associated contacts into the thirteenth position, 90 whereupon they are returned to their normal or first position through the influence of the interrupter 311 and the sequence 95 switch contact 312 (positions 13 to 18 inclusive).

It will be noted that the series of impulses representing the digits 5836 as registered were transmitted to the selector 100 switches on the local trunk 102 in the reverse order, that is as 6385, which is the abbreviated numerical designation of the called line. The digits 153 which characterize this group were not transmitted or in 105 other words were automatically taken care of in the arrangement of the system.

It will now be shown how the addition of the digits 271 (the reverse of 172) will cause the substation having the same curtailed designation as the called substation just described but in a group characterized by the digits 172 to be called.

The description of the registering of the digits 5836 in this case will be similar in 115 every respect to that previously given. When, however, the circuit for the energization of the relay 221 is established, a difference in action will occur. In the present case a series of two short impulses will be 120 transmitted from the substation 100 before the relay 221 can attract its armatures. These two short impulses will cause the actuation of relay 220 and in turn the motor magnet 224 in such a manner that the sequence switch under control of motor magnet 224 will be driven into its fourth position and the contact 223 (position 4) will be closed. As the sequence switch moves 125 out of position 2 the energizing circuit for 130

the relay 221 will be opened. At the end of this series of impulses, the slow acting relay 226 will become deenergized and in turn the relay 227 will be energized, whereupon the circuit leading over conductors 202 and 203 to the substation will be switched to a sixth register.

In a manner similar to that described the sixth register will be moved to its ninth position, thereby registering the digit 7.

At the completion of this registration, the relay 230 will become energized and in a manner similar to that described, the sequence switch under control of the motor magnet 234 will be moved to its third position and the contact 233 (position 3) will be closed. When the digit 1 is thus registered the slow release relay 236 will become deenergized and will cause the energization of the relay 237.

Thereupon, the trunk leading to the substation will be switched into association with the relay 350.

Through a circuit extending from ground, the right-hand winding of relay 350, sequence switch contact 351 (position 1), alternate contact and outer left-hand armature of relay 237, alternate contact and outer left-hand armature of relay 227, normal contact and inner right-hand armature of relay 221, alternate contact and outer left-hand armature of relay 211, alternate contact and outer left-hand armature of relay 201, conductor 203, brush 134, contact 133, third position contact and side-switch wiper 132, brush 116, terminal 125, to and through the apparatus of the substation 100, terminal 126, brush 117, side-switch wiper 131 and its third position contact, contact 130, brush 129, conductor 202, inner left-hand armature and alternate contact of relay 201, inner left-hand armature and alternate contact of relay 211, outer right-hand armature and normal contact of relay 221, inner left-hand armature and alternate contact of relay 227, inner left-hand armature and alternate contact of relay 237, sequence switch contact 352 (position 1), left-hand winding of relay 350, battery and ground, relay 350 is energized.

Thereupon, a circuit is established from ground, contact and armature of relay 350, winding of motor magnet 353 to battery and ground, whereupon the sequence switch under control of this motor magnet is moved to its second position. Under control of sequence switch contacts 359 and 360 a path of low resistance is placed between the terminals 150 and 151 of the long distance trunk 103. This circuit may be traced from terminal 150, normal contact and upper outer armature of relay 111, contact 139, brush 140, conductor 141, sequence switch contact 359 (positions 2 to 17), sequence switch contact 359 (position 2), sequence switch contact 360

(position 2), sequence switch contact 360 (positions 2 to 17), conductor 142, brush 143, contact 144, inner upper armature and normal contact of relay 111, to terminal 151.

In position 2 of the sequence switch under control of motor magnet 353, a circuit is established from ground, interrupter 311, sequence switch contact 354 (position 2), winding of motor magnet 353 to battery and ground, whereby the sequence switch is moved to its third position. In the third position a circuit is established from ground, sequence switch contact 355 (position 3), contact and right-hand armature of relay 314, winding of relay 314 to battery and ground.

The subsequent action of the sequence switch under control of motor magnet 353 and the impulse transmitter is similar to that previously described. Through the sequence switch contacts 356 and 357, the registers starting with the seventh are grounded in turn, the brush 315 is caused to travel over its contacts, the magnet 314 is caused to interrupt a line circuit over conductors 141 and 142 in accordance with the registered digits until the digit 5 which was the first to be registered is retransmitted over the long distance trunk 103 to the connector switch thereof.

As the brush 315 reaches its normal position, after five interruptions of the line circuit have been caused in response to the setting of the first register, the sequence switch under control of motor magnet 353 will be moved to the seventeenth position, whereupon a circuit will be established from ground, battery, sequence switch contact 300 (position 17), conductor 114, brush 113, contact 112, through the winding of primary magnet 110, winding of escape magnet 121, side-switch wiper 120 in its third position, contact 147, brush 146, the left-hand armature of relay 145, conductor 323, sequence switch contact 358 (position 17), to ground. Through this circuit the escape magnet 121 will be energized and the side-switch wipers will thereupon be moved into their fourth positions where the calling substation 100 will be directly extended to the long distance trunk 103.

In the fourth position of the line finder side-switch wipers a circuit is established from ground, fourth position contact and side switch wiper 148, contact 147, brush 146, winding of relay 145, to battery and ground. Relay 145 attracts its armatures and establishes a circuit heretofore described for the energization of stepping magnet 149. Thereafter the action of the allotter switch is the same as before and the action of the registers and impulse transmitter in their return to normal is the same.

At the conclusion of the conversation held either over the long distance trunk 103 or

the local trunk 102, the connection is restored in the usual manner. This may be accomplished by placing a ground on the third or test conductor, which, upon being transmitted through the outer lower armature of relay 111 through the armature and contact of relay 154, the off-normal contact 155, the winding of release magnet 156 to battery and ground, will cause the line 10 finder switch to be restored to its normal condition.

What is claimed is:

1. In a telephone exchange system, lines arranged in numerical order accessible to 15 calling lines by composite paths comprising a plurality of simple paths, selective switches arranged to select a composite path by means of successive selections of simple paths, the number of selections being greater than the 20 number of characters in the designation of the line to which such path is to be extended.

2. In a telephone exchange system, lines arranged in numerical order divided into groups and accessible to calling lines of all 25 but the same group by composite paths comprising a plurality of simple paths, the number of which is greater than the number of characters in the full designation of the line to which such path is to be extended and accessible to calling lines of the same group by 30 composite paths comprising a plurality of simple paths, the number of which is greater than the number of characters in the abbreviated designation of the line to which 35 such path is to be extended and less than the number of characters in the full designation of the line to which such path is to be extended.

3. In a telephone exchange system, lines 40 arranged in numerical order, a calling device associated with each of said lines, registers responsive to said calling devices, impulse transmitters responsive to said registers, selective switches for interconnecting 45 said lines responsive to said impulse transmitters, said impulse transmitters being arranged to transmit series of impulses in the reverse order to which they are registered.

4. In a telephone exchange system, lines 50 arranged in numerical order and divided into groups, a full and a curtailed designation for each of said lines, means responsive to the transmission of impulses representing the full designation for extending 55 a calling line in one group over a trunk leading to a second group, and means responsive to the transmission of impulses representing the curtailed designation for extending a calling line in said second 60 group over a trunk leading to the same group.

5. In a telephone exchange system, lines arranged in numerical order, a designation 65 for each of said lines, selective switches for interconnecting said lines, means for set-

ting said switches in accordance with the digits of said designations, and means for making an additional selection in accordance with the number of digits in said designation.

70

6. In a telephone exchange system, lines arranged in numerical order, selective switches for interconnecting said lines, a designation for each of said lines comprising a plurality of digits, and means for setting said switches on the terminals of a called line through the use of less than the full number of digits comprising the designation of that line.

75

7. In a telephone exchange system, lines 80 arranged in numerical order each provided with a designation listed in the reverse order, subscriber controlled means for registering such reversed designations, selective switches for interconnecting said lines, 85 means responsive to said registering means for setting said selective switches, and means for causing such setting to take place in the reverse order to that in which said registers were set.

90

8. In a telephone exchange system, an exchange district, lines arranged in numerical order within said district, a full number of designations for such lines comprising a given number of characters in all possible 95 permutations, selective switches for interconnecting said lines responsive to series of impulses representing such designations, said switches being arranged to a capacity equal to the said full number of designations, foreign districts, a series of longer 100 designations for use in calling lines in said foreign districts, and means responsive to series of impulses representing such longer designations for extending said lines to said 105 foreign districts.

9. In a telephone exchange system, lines arranged in numerical order and divided into groups, selector switches for interconnecting said lines arranged in order for successive actuation, a designation for each of said lines comprising a full number of characters for use in intergroup calling, means for actuating said selector switches starting with the first in order, an abbreviated 110 designation for each of said lines comprising less than the full number of the same characters for use in intragroup calling, and means for actuating said selector switches starting with a later one than the 115 first in order.

10. In a telephone system, telephone lines, and means for interconnecting said lines comprising means for selecting a line responsive to the number of characters in the 120 designation of a called line and other means for selecting lines responsive to the characters in the designation of a called line.

125

11. In a telephone system, telephone lines and means for interconnecting said lines 130

comprising means for making a primary selection of lines in the direction of the called line responsive to the number of characters in the designation of the called line, and selective switches for making the final selection of lines in the direction of the called line responsive to the characters in the designation of the called line.

12. In a telephone system, telephone lines, 10 said telephone lines being identified for pur-

poses of calling by designations containing varying numbers of characters, machine switching means for interconnecting said lines, and means responsive to the number of characters in the designation of a called 15 line for selecting a trunk to a train of selective switches of a corresponding number.

In witness whereof, I hereunto subscribe my name this 20th day of July, A. D. 1917.

JOHN A. HALL.
